UNITED STATES PATENT OFFICE.

WILLIAM H. HENDRICK, OF ST. LOUIS, MISSOURI, ASSIGNOR TO THE N. O. NELSON MANUFACTURING COMPANY, OF MISSOURI.

DESIGN FOR A VALVE-CASING.

SPECIFICATION forming part of Design No. 24,639, dated August 27, 1895.

Application filed May 16, 1895. Serial No. 549,590. Term of patent 3½ years.

To all whom it may concern:

Be it known that I, WILLIAM H. HENDRICK, a citizen of the United States, and a resident of the city of St. Louis, in the State of Missouri, have invented and produced a new and original Design for a Valve-Casing, of which the following is a specification, reference being had to the accompanying drawing, forming a part thereof.

The drawing is an elevation showing my design for a valve-casing.

The leading feature of my design consists in a valve-casing representing three superposed bulbs surmounted by an upwardly-flaring head.

1 2 3 represent three superposed bulb-shaped portions, and 4 is an upwardly-flaring head surmounting the bulb-shaped portion.

Having thus described my invention, the following is what I claim as new therein and desire to secure by Design Letters Patent:

The design for a valve-casing substantially as herein shown and described.

WM. H. HENDRICK.
